COMBINED LOUDSPEAKER ENCLOSURE AND AMPLIFIER HOUSING

Charles A. Ross, Fort Scott, Kans., assignor to Road
Electronics, Inc., Fort Scott, Kans.

Filed Dec. 16, 1974, Ser. No. 533,006

Term of patent 14 years

Int. Cl. D14—01, 03

U.S. Cl. D26—14 G

Fig. 1

*Fig. 2*FIG. 1 is a front perspective of a combined loudspeaker enclosure and amplifier housing showing my new design; and

FIG. 2 is a front elevation of the loudspeaker enclosure. The undisclosed side and rear portions of the combination unit are plain and unornamented.

I claim:

The ornamental design for a combined loudspeaker enclosure and amplifier housing, as shown and described.
